Application filed December 29, 1931. Serial No. 42,297. Term of patent 3½ years.

To all whom it may concern:

Be it known that I, CHARLES MILLER, a citizen of the United States, and resident of the city of New York, county of New York, and State of New York, have invented a new, original, and ornamental Design for a Shoe, of which the following is a specification, reference being had to the accompanying drawings, forming part thereof.

Fig. 1 is a front perspective view of a shoe, showing my new design; and

Fig. 2 is a side perspective view of the same.

The dominant feature of the design is the ornamental effect produced by the portions extending as continuations of the lacing along the sides of the shoe to the shank portion thereof.

I claim:

The ornamental design for a shoe, substantially as shown and described.

CHARLES MILLER.
